(57) **CLAIM**

The ornamental design for microneedle array, as shown and described.

DESCRIPTION

FIG. 1 is a front view of a microneedle array showing our new design;

FIG. 2 is a rear view thereof;

FIG. 3 is a right side elevational view thereof;

FIG. 4 is a left side elevational view thereof;

FIG. 5 is a top plan view thereof;

FIG. 6 is a bottom view thereof;

FIG. 7 is a first perspective view thereof; and,

FIG. 8 is a second perspective view thereof.

The broken lines depict portions of the microneedle array that form no part of claimed design.

1 Claim, 8 Drawing Sheets
